UNITED STATES PATENT OFFICE

CARL F. GOUDY, OF FLUSHING, NEW YORK, ASSIGNOR TO PAGENT ELECTRIC COMPANY, INC., OF NEW YORK, N. Y., A CORPORATION OF NEW YORK

CONNECTION FOR POWER AMPLIFIERS

Application filed June 22, 1926. Serial No. 117,656.

This invention relates to the use of power amplifiers with radio receiving sets.

In adding to the average receiving set a power amplifier embodying a stage of audio frequency amplification, it has usually been found advisable to eliminate the audio frequency stages or at least the last audio-frequency stage in the receiving set. Where the receiving set is equipped with jacks in the 10 detector or first audio stages, this is a simple matter. A great many sets, however, are not equipped with jacks or other outlets at these points and the present invention aims to provide simple and readily adaptable means by 15 which the power amplifier may be connected in with the detector or first audio stage in those receiving sets which are not equipped for such a connection.

More particularly, the invention is concerned with receiving sets equipped with the flat top style of sockets designed for the so-called "U. X." tubes now largely used.

Special objects, therefore, are to provide an adapter which can be plugged into a tube 20 socket and which will provide an outlet from the plate or output side of the tube directly to the power amplifier, thus by-passing the following stages in the set.

A special feature of the invention is the 30 construction of the device in the nature of an adapter plug having contact sockets at its upper side to receive the usual four prongs of the tube and having at its under side only three of the usual four prongs, these designed to fit into the socket and the fourth or plate prong being left off and in its stead a wire connection being provided for carrying off the output of the tube directly to the power amplifier.

Various other novel features of the invention will appear as the specification proceeds.

The drawings accompanying and forming part of this specification illustrates one practical embodiment of the invention and it should be understood that the structure may be modified without departure from the true spirit and scope of the invention as herein-after defined and broadly claimed.

Figure 1 is a schematic representation of

a typical U. X. socket five tube receiving set illustrating the invention in use for by-passing the last audio-frequency stage and for carrying the output of the first audio stage directly to the power amplifier.

Figure 2 is a cross sectional view of the device as plugged into the tube socket and carrying the tube, this view being taken as on substantially the line 2-2 of Figure 3.

Figure 3 is a top plan view of the plug member of the connection.

Figure 4 is a bottom plan view of the same.

Figure 5 is a side elevation of the adapter.

Figure 6 is a plan view of the tube socket to which the connection is applied.

The radio receiving set indicated generally at 7 in Figure 1 is of a usual type embodying two radio frequency tubes 8, 9, a detector tube 10 and first and second audio-frequency tubes 11, 12. These tubes are all shown mounted in tube sockets 13.

The sockets illustrated are of special design in that they have approximately circular cap pieces 14 yieldingly supported on the bases 15 by means of combined contact and terminal springs 16, the cap pieces having two large and two small openings 17, 18, respectively, to receive the corresponding large and small prongs of the tube.

The by-passing adapter is designed to plug into the socket after the manner of a tube and is equipped with socket contacts to itself receive the tube.

In the illustration the body of the adapter is a flat insulating member 19, like the cap piece of the socket, preferably the same as that piece so that the two may be used interchangeably for tube sockets or with this special adapter. Both these parts have a dependent central stud or hub 20 receiving a screw 21, which, in the case of the socket, secures a bottom plate 22 thereto and in the case of the adapter, secures a contact and terminal supporting plate 23 thereto. The bottom plate 22 of the socket supports and positions the upstanding socket springs 16 which normally are engaged by the prongs of the tube.

In similar fashion, the lower plate 23 of

the plug carries the four contact springs 24, 25, 26, 27 corresponding in position and location to the socket contacts and extending upwardly into the prong sockets 28, 29, 30, 31 respectively in the top of the plug. The first two of these sockets are of the larger size corresponding to sockets 17 in the tube socket and the second pair are smaller in size corresponding to the smaller sockets 18. The adapter is thus equipped to receive the prongs of the tube in the same manner as the tube socket.

Three of the adapter springs, namely, those numbered 24, 25 and 26 are riveted or otherwise secured to prongs 32, 33 and 34, projecting downwardly from the base plate 23 similar to the corresponding three prongs of a tube. The fourth contact, 27, which becomes the output or plate terminal when the tube is inserted in the base of the adapter, has no prong extension and instead, a wire extension 35 is secured to the foot of the same at 36 above the base plate, which wire is shown as passed upwardly and out through a guide opening 37 extending upwardly and out through the side of the adapter.

At its free end the extension wire 35 is preferably equipped with a terminal 351 having a socket to receive a telephone cord tip or wire end held in place by a set screw 38.

The receiving set shown is illustrated as having an output jack 39 which ordinarily would have one terminal connected with the positive side of the high voltage or "B" battery of the set. Therefore, it is possible to use this one terminal of the jack in making connection with the power amplifier. A telephone plug 40 is therefore shown inserted in this jack, having one side 41 of a telephone cord 42 connected thereto and the other terminal 43 of the other side of this cord is shown engaged in the socket of the extension wire terminal 351. The cord, 42, thus becomes a connection for carrying the output of the receiving set to the power amplifier, said cord being illustrated as having at its other end, a telephone plug terminal 43, entered in the input side of the power amplifier, indicated at 44. The output from this amplifier is shown connected by a suitable cord circuit 45 with the speaker 46. This power amplifier may be of any usual or special type and is indicated as embodying a rectifier tube 47 and an amplifier tube 48, said tubes receiving energy from a cord circuit 49 designed to be plugged in on the ordinary house lighting system.

To use the invention it will be seen that it is only necessary to remove the detector or the first audio tube, depending upon whether both audio stages or only the last audio stages are or is to be eliminated and to insert in the vacated socket, the three pronged adapter, after which the tube is inserted in the adapter and the connection from the

adapter is engaged with the free terminal of the telephone cord.

The adapter should be inserted in the socket with its prongs positioned to correspond with the prongs of the tube for which it has been substituted so that when the tube is inserted into it, the proper connections will result. Accordingly, the adapter is preferably marked with an arrow 50 or the like just as is the socket so that when the plug is inserted in the socket with the arrows in alignment, the output prong of the tube will engage with the extension cord contact of the adapter when the tube is inserted.

The adapter structure is simple and durable and relatively inexpensive, particularly so because of the fact that duplicate parts may be used in adapters and sockets. The device furthermore occupies but small space and the extension wire is small so that it may be brought out over the top or at the back of the usual front panel.

What is claimed is:

1. In a device of the character disclosed, a flat plug base having prong passages through the top thereof, a flat insulating plate spaced below and secured to the under side of said base, contact springs projecting upwardly from said plate into the prong sockets, an extension wire connected with one of said contact springs and prongs corresponding to tube prongs projecting from the plate and connected with the other contact springs.

2. In a device of the character disclosed, a plug base having prong passages in the top thereof, an insulating plate at the under side of said base, contact springs projecting upwardly from said plate into the prong sockets, an extension wire connected with one of said contact springs and prongs corresponding to tube prongs projecting from the plate and connected with the other contact springs, said insulating plate being spaced below the plug member by an insulating stud, the extension wire being located in said space and the plug member having an opening extending from underneath out through the side of the same for said extension wire.

3. An adapter of the character disclosed, comprising a plate of insulating material, prongs corresponding to radio tube prongs projecting downwardly from said plate, a flat insulating cap having prong passages therethrough, means securing said cap member in spaced relation above said insulating plate, spring contacts carried by said insulating plate and having their upper ends projecting upwardly into the prong passages in the cap member, electrical connections between some of said contacts and prongs, and a wire connected with and extending off from a contact insulated from all the prongs.

In witness whereof, I have hereunto set my hand this 18th day of June, 1926.

CARL F. GOUDY.
